UNITED STATES PATENT OFFICE.

ALBERT HAENTZE, OF CHICAGO, ILLINOIS.

MAIL-RECEIVING BOX.

No. 851,745.

Specification of Letters Patent. Patented April 30, 1907.

Application filed January 24, 1907. Serial No. 353,793.

To all whom it may concern:

Be it known that I, ALBERT HAENTZE, a citizen of the United States, residing in Chicago, Cook county, Illinois, have invented 5 certain new and useful Improvements in Mail-Receiving Boxes; and my invention relates more particularly to that class of mailbox adapted for receiving and holding newspapers which are distributed by carriers who are to put them into such receptacles to keep them from being blown away or becoming wet in rain or snow, where the owner may take them out at his leisure, and of which the following is a full and correct specification, 10 reference being had to the hereto accompanying drawing, forming a part hereof, and in which—

Figure 1 shows my said new device in elevation, partly in section; Fig. 2 shows a plan 20 view of the lower end of said device when looking into it at its open end, with its gate closed. Fig. 3 shows the gate *e* as seen from its hinge end.

Like reference letters denote like parts 25 throughout.

To attain said desired ends I construct my said new newspaper mail-box in substantially the following manner, namely; I make a cylindrical box *a*, preferably, of galvanized 30 iron. Said cylinder is closed water tight above but is open at its bottom end, and at said end is provided with from one to several circumferential corrugations *b* and a hinge *d* into which pass the two ends *e'* of a wire 35 which are provided with short spurs *e* at their meeting ends, and which point inward or at right angles to said parts *e'*, their purpose being to prevent the parts *e'* from drawing out of the hinge. From said hinge said 40 wire crosses in a horizontal plane in two members until the opposite side of the cylinder is reached, then each part rises vertically to said plane and projects outward in a curved form seen at *g* which fits onto the top side of 45 a corrugation *b*, one of said vertical parts be-

ing on each side of the slot *c*. From said parts *g* which constitute a catch the said wires approach forming short horizontal elements *f* from which, at the center of the slot *c* said parts turn and project outward through 50 said slot and form a loop *h* which projects beyond the outside of said cylinder a sufficient distance to form a handle to operate said gate *e* which turns on the hinge *d* as shown in Fig. 1, and which, when closed, secures news- 55 papers and holds them as stated and, at the same time, is a mechanism which is readily and easily operated. Said corrugated cylinder and end gate, together, have sufficient elasticity to permit said catch *g* to spring 60 onto a corrugation *b* by the application of convenient force to either open or close said gate. The outer ends of said hinge project laterally to form lugs *j* through which pass 65 nails to secure the device to a suitable support and a lug *k* at the top of the holder serves a like purpose to hold the upper end of the device.

What I claim is:

1. The combination with a cylinder pro- 70 vided at its lower end with circumferential corrugations and a vertical slot and a hinge opposite said slot, of a gate made of a single piece of wire with ends entering said hinge from its opposite ends and said gate, oppo- 75 site said hinge, provided with substantially vertical projections *g* to catch and hold on said corrugations and a loop projecting through said slot.

2. The combination with a cylinder pro- 80 vided at its lower end with a vertical slot, a hinge, and means to form a yielding catch at said slot, of a single-piece wire gate entering said hinge from opposite ends, and a handle projecting therefrom through said slot.

ALBERT HAENTZE.
